(57) **CLAIM**

The ornamental design for an inflatable swimming pool with handles as shown and described.

DESCRIPTION

FIG. 1 is a top perspective view of the inflatable swimming pool with handles showing the present design.

FIG. 2 is a front view thereof.

FIG. 3 is a rear view thereof.

FIG. 4 is a right view thereof.

FIG. 5 is a left view thereof.

FIG. 6 is a top view thereof; and,

FIG. 7 is a bottom view thereof.

The broken lines show portions of the inflatable swimming pool with handles and form no part of the claimed design.

1 Claim, 5 Drawing Sheets
